UNITED STATES PATENT OFFICE.

DONALD BARNES MORISON, OF HARTLEPOOL, ENGLAND.

STEAM REGENERATIVE ACCUMULATOR.

1,095,913.

Specification of Letters Patent.

Patented May 5, 1914.

Application filed March 8, 1911. Serial No. 613,056.

To all whom it may concern:

Be it known that I, DONALD BARNES MORISON, a subject of the King of Great Britain and Ireland, residing at Hartlepool, in the 5 county of Durham, England, have invented a Steam Regenerative Accumulator, of which the following is a specification.

My invention relates to heat storage and steam regenerating apparatus and has for 10 object to beneficially utilize surplus steam which ordinarily escapes to the atmosphere through a safety valve, by causing such surplus steam or a part thereof, when a desired pressure is reached, to beneficially heat 15 liquid, for example boiler feed water, and so increase the thermal efficiency of the system, the resistance being provided by a valve or by a head of water or by both in combination.

20 My invention may be carried out in various ways and is generally applicable to steam regenerative accumulators of any type.

The accompanying drawings illustrate diagrammatically applications of my invention to a steam regenerative accumulator of the type in which the exhaust steam passes into a body of water. Figure 1 being a longitudinal section partly in elevation, Fig. 2 a longitudinal section of a modification 30 with certain parts omitted, and Fig. 3 a sectional detail view illustrating a further modification.

In Fig. 1, *a* is a high pressure steam engine, *b* its exhaust pipe, *c* the heat accumulator, *d* its submerged nozzles, *e* the regenerated steam outlet pipe, *f* a low pressure turbine and *g* a condenser. *h* is a chamber into which boiler feed water is delivered through a pipe *i* from any suitable source 35 and from which it passes out through a pipe *j*; submerged in the feed water are heating nozzles *k* through which steam from the exhaust pipe *b* flows; the head of water above the nozzles *k* corresponding to the depth at 40 which the steam outlets therefrom are submerged below the water level in the chamber *h*, offers a higher resistance to the discharge of steam from the nozzles *k* than from the nozzles *d* which have their steam 45 outlets submerged at a lesser depth below the level of the water in the accumulator *c* and therefore the steam from the exhaust pipe *b* preferentially passes through the nozzles *d* into the water in the accumulator, but 50 when the pressure in the steam space of the accumulator increases and the resistance to

the flow of steam from the nozzles *d* is equal to a predetermined pressure corresponding to the total resistance to flow through the nozzles *k*, the surplus steam passes to and 60 heats water in the chamber *h*. The chamber *h* has connected to it the pipe *l* through which any uncondensed steam may escape to the atmosphere, and the heat accumulator *c* is provided with a safety valve *n*, which 65 may be arranged to operate in combination with the heating nozzles *k* either in series or in parallel.

When the pressure of the head of water represented by the vertical distance from the 70 level of the water in the chamber *h* to the horizontal portion of the pipe *b*¹ is less than that corresponding to the low limit of pressure in the pipe *b* a non-return valve *m* is provided so as to prevent the back flow of 75 water from the chamber *h* into the steam supply system when such low limit pressure is reached.

According to the arrangement illustrated in Fig. 1 steam passes from the exhaust pipe 80 *b* through the nozzles *d* and into the water in the heat accumulator *c*, but when the volume of the steam flowing through the exhaust pipe *b* is greater than can be utilized by the low pressure turbine *g* and the heat 85 accumulator *c*, then the pressure in the steam space of the accumulator rises until the pressure in the exhaust pipe *b* is greater than the back pressure offered to the escape of steam through the valve *m* and nozzles 90 *k*, when steam will pass through the valve *m* and nozzles *k* and be condensed by the feed water in the chamber *h* which is thereby beneficially heated. Steam may also be delivered from the accumulator *c* into the 95 water in the chamber *h* by a pipe *o* the end of which is below the level of the nozzles *k* and is fitted with a non-return valve *p* that closes and prevents the back flow of water 100 into the accumulator *c* when the pressure in the accumulator falls. The pipe *o* may pass downwardly through the water in the accumulator and have openings *o*¹ at the required water level, so that should the water 105 in the accumulator rise above the level it will flow through the openings *o*¹ into the chamber *h*.

Fig. 2 shows another arrangement according to my invention in which *c* is the heat accumulator, *d* its submerged nozzles, 110 *b* the exhaust steam pipe from a high pressure engine, and *e* the steam outlet pipe to

the low pressure turbine. *h* is a chamber containing feed water which has been sprayed from the pipe *i* and which passes out through the pipe *j*; the chamber *h* is formed independently of the accumulator *c* but is connected to the steam space therein by the pipe *b*¹ in which is disposed the loaded valve *m* which, allows the passage of steam to said chamber only when the pressure in the steam space of the accumulator rises above the predetermined pressure limit at which it is desired to allow steam to escape therefrom, any steam not condensed in the chamber *h* being free to escape to the atmosphere through the pipe *l*.

Fig. 3 shows another form of the chamber *h* shown in Fig. 2. In this example the pipe *b*¹ which is connected directly to the steam space in the accumulator *c* is led into the chamber *h* below the water level and is provided with a non-return valve *m*, the face of such valve being situated below the water level in order to water seal the valve and prevent leakage of air through the pipe *b*¹ into the steam space of the accumulator *c* when the pressure therein falls below the pressure in the chamber *h*, the valve *m* being loaded so that it opens only when the pressure in the steam space in the accumulator exceeds the limit of pressure at which it is desired to allow the surplus steam to pass into and be condensed by the feed water entering the chamber *h*.

What I claim is:—

1. The combination with a steam regenerative accumulator of a liquid heating chamber, an exhaust steam connection to said accumulator, an exhaust steam connection to said chamber, a pressure relieving device arranged to allow the passage of exhaust steam to said liquid heating chamber through said latter connection only when the pressure of said exhaust steam exceeds a predetermined limit and to prevent return flow of steam, and means arranged to prevent liquid passing from the liquid heating chamber to the accumulator.

2. The combination with a steam regenerative accumulator of a liquid heating chamber, exhaust steam connection to said accumulator and chamber, a pressure relieving device which allows the passage of steam to said liquid heating chamber only when the pressure of said steam exceeds a predetermined limit and a non-return valve in the steam connection to said chamber, which valve is water sealed when the pressure in the exhaust steam connection falls below a predetermined limit.

3. The combination with a steam regenerative accumulator of a liquid heating chamber, exhaust steam connection to said accumulator and chamber, a pressure relieving device which allows the passage of exhaust steam to said liquid heating chamber

70
ber only when the pressure of said exhaust steam exceeds a predetermined limit, a non-return valve in the steam connection to said accumulator and chamber and an outlet from said chamber to atmosphere.

4. The combination with a steam regenerative accumulator of a liquid heating chamber, exhaust steam connection to said accumulator and chamber, a pressure relieving device which allows the passage of steam to said liquid heating chamber only when the pressure of said steam exceeds a predetermined limit, the said pressure relieving device being water sealed so as to prevent air passing from said chamber to the accumulator and an outlet from said chamber to atmosphere.

75
5. The combination of a liquid containing steam regenerative accumulator, submerged nozzles therein, an exhaust steam supply to said nozzles, a liquid heating chamber, nozzles submerged therein to a greater depth than those in the accumulator and a connection between said exhaust steam supply and the nozzles in said liquid heating 90 chamber.

6. The combination of a liquid containing steam regenerative accumulator, submerged nozzles therein, an exhaust steam supply to said nozzles, a liquid heating chamber, nozzles submerged therein to a greater depth than those in the accumulator and a connection between said exhaust steam supply and the nozzles in said liquid heating chamber said connection being provided with a 100 non-return valve opening toward said chamber.

7. Apparatus for condensing exhaust steam and heating liquid comprising a steam regenerative accumulator, a feed 105 water heater, nozzles submerged in liquid in the accumulator, nozzles submerged to a greater depth in the feed water in the heater, a pipe for connecting the accumulator nozzles with the exhaust steam supply, and a 110 pipe connection to the water heater for relieving the steam pressure by the passage of steam through the water heater nozzles.

8. Apparatus for condensing exhaust steam and heating liquid comprising a 115 steam regenerative accumulator, a feed water heater, steam heating nozzles submerged in liquid in the accumulator, a valve connecting the steam space of the accumulator with the water heater adapted to open 120 and allow steam to pass to and heat water in the water heater when a predetermined pressure is reached in the accumulator.

9. Apparatus for condensing exhaust steam and heating liquid comprising a 125 steam regenerative accumulator, a feed water heater, steam heating nozzles submerged in liquid in the accumulator, a pipe connecting the steam space of the accumulator with the water heater, a pressure re- 130

lieving device comprising a non-return valve which allows the passage of exhaust steam into the water in the heater when the pressure in the accumulator rises above a predetermined limit.

10. Apparatus for condensing exhaust steam and heating liquid comprising a steam regenerative accumulator, steam heating nozzles submerged in liquid in the 10 accumulator, a chamber adapted to contain liquid to be heated, a pipe leading downward at the required water level in the accumulator to below the water level in the chamber and fitted with a non-return valve, 15 said pipe being adapted to pass surplus steam and water from the accumulator into said chamber.

11. The combination of a liquid containing steam regenerative accumulator, an exhaust steam supply to said regenerative accumulator, a liquid heating chamber, nozzles submerged therein and a connection between said exhaust steam supply and the nozzles in said liquid heating chamber.

25 12. The combination of a liquid containing steam regenerative accumulator, an exhaust steam supply to said accumulator, a liquid heating chamber, nozzles submerged therein, a connection between said exhaust 30 steam supply and the nozzles submerged in said heating chamber and a valve in said connection.

13. The combination of a liquid containing steam regenerative accumulator, submerged nozzles therein, an exhaust steam supply to said nozzles, a liquid heating chamber and a connection between the accumulator above the liquid level therein and the liquid space of said heating chamber, 40 the heating chamber end of said connection being submerged to a greater depth than the nozzles in the accumulator.

14. The combination of a liquid containing steam regenerative accumulator, submerged nozzles therein, an exhaust steam supply to said nozzles, a liquid heating chamber and a connection between the accumulator above the liquid level therein and

the liquid space of said heating chamber, the heating chamber end of said connection 50 being submerged to a greater depth than the nozzles in the accumulator and a non-return valve controlling said connection.

15. The combination with a steam regenerative accumulator of a liquid heating 55 chamber, exhaust steam connection to said accumulator and chamber, submerged steam outlets in the heating chamber adapted to allow the passage of steam to the latter only when the pressure exceeds a predetermined 60 limit, means preventing liquid and steam passing from said heating chamber to the accumulator and a safety valve adapted to allow the escape of steam from the accumulator to the atmosphere when a still higher 65 pressure of steam arises.

16. The combination of a liquid containing steam regenerative accumulator, an exhaust steam supply to said accumulator, a liquid heating chamber, a connection between the accumulator above the liquid level 70 therein and the liquid space of said heating chamber said connection being adapted to relieve the pressure in the accumulator when it exceeds a predetermined pressure and 75 means preventing liquid and steam passing from said heating chamber to the accumulator.

17. The combination of a liquid containing steam regenerative accumulator, an exhaust steam supply to said accumulator, a liquid heating chamber, a connection between the accumulator above the liquid level therein and the liquid space of said heating chamber, said connection being adapted to 80 relieve the pressure in the accumulator when it exceeds a predetermined pressure and in 85 said connection, means adapted to prevent liquid and steam passing from said heating chamber to the accumulator. 90

Signed at West Hartlepool this twenty-third day of February 1911.
